UNITED STATES PATENT OFFICE

2,457,950

ELECTRONIC DEVICE

Albert G. Thomas, Lynchburg, Va.

Original application January 18, 1945, Serial No. 573,366. Divided and this application November 15, 1945, Serial No. 628,784

12 Claims. (Cl. 250—27.5)

1

This invention relates to electronic devices generally and particularly to electronic switches and is a division from my co-pending application Serial No. 573,366, filed January 18, 1945, now Patent No. 2,432,260.

The usual type of electro-mechanical switch is far too slow in operation for many purposes and has the disadvantage that the contacts burn and wear rapidly under heavy loads. It is therefore an object to provide an electronic switch which may be easily connected in circuit and which will operate with great rapidity.

Another object is to provide a simple electronic switch which can be substituted for complicated arrays of tubes and other components which, in the past, have been used in attempts to accomplish similar results.

A further object is to provide an electronic switch in which poles can be inter-connected or crossed over as desired.

Another object is to provide an electronic switch with a plurality of chambers with inter-connecting channels which may be electrically connected or disconnected.

An additional object is to provide a double pole reversing electronic switch.

Other objects will appear in the specification.

The drawing shows an electronic switch, with casing and crossed partitions in section, and having a plurality of interconnected chambers containing various switch elements.

In the drawing, envelope 1 has cross partition 29 of glass or the like and glass partitions 2 and 3 sealed to the inside of the envelope and to partition 29, forming chambers A, B, C and D as shown. Channels or openings 25 and 28 in partition 29 join chambers A and B and chambers C and D respectively. Likewise, inclined channels 26 and 27 in partition 29 join chambers B and C, A and D, respectively. Grids 4 and 9 are positioned in openings 28 and 25, respectively and are connected with suitable leads 7 and 8 sealed in envelope 1. These grids could be placed near the openings, on either side of partition 29.

Grid 10 is placed near the lower end of opening 27, although it can be situated in the opening, and is connected with lead 11 and sealed in envelope 1 and partition 3. Similarly, grid 5 is placed near the lower end of opening or channel 26, although it could be in the channel, and is connected with lead 6 sealed in partitions 29, 2, and envelope 1. These leads could be brought out in other manner if desired.

Anodes 18 and 19, with leads 20 and 21, are provided in chambers B and D, respectively, and

cathodes or filaments 12 and 13 with leads 14—15 and leads 16—17, are provided in chambers A and C, respectively. These cathodes may be connected by conductor 24 sealed in envelope 1, or snapped in an outside recess. Then the cathodes may be energized in series by connecting leads 14 and 16 to a current source, or in parallel by employing leads 14—15 and 16—17. Screens 22 and 23, with connected leads sealed in envelope 1, may be provided. The chambers may contain gas or they may be highly evacuated.

In operation, considering an evacuated device, if grids 10 and 5 are made negative with respect to cathodes 12 and 13, and if grids 9 and 4 are made positive with respect to the cathodes by connecting them to suitable potential sources or otherwise, then flow of electrons through passages 26 and 27 can be prevented and flow of electrons from cathode 12 to anode 18, through passage 25, can be induced or allowed by grid 9. Similarly, positively charged grid 4 will induce or allow flow of electrons from cathode 13 to anode 19 through passage 28. If grids 9 and 4 are charged sufficiently negatively then virtually all current flow through passages 25 and 28 will cease. The amount of electron flow can be controlled by the kind and degree of charges on the grids.

Now if grids 9 and 4 are negatively biased to stop flow of electrons through passages or channels 25 and 28 and if grids 10 and 5 are made positive (or less negative) with respect to the cathodes sufficiently to allow flow of electrons through passages 27 and 26, respectively, then electrons from cathode 12 will flow through passage 27 to anode 19 and electrons from cathode 13 will flow through passage 26 to anode 18. The strength of the currents can be regulated by the charges on the grids.

This device therefore can be made to function as an electronic double pole reversing switch the currents through which may be regulated in both direction and strength. This furnishes a highly flexible relay or switching device for use in circuits generally.

The positive terminal of a common source of potential can be connected to anodes 18 and 19 through a load for each anode, the negative terminal of the source being connected to one of the leads of the joined cathodes. In this way, fields can be established between cathode 12 and anode 18 and between cathode 12 and anode 19 and between cathode 13 and anode 19 and also, between cathode 13 and anode 18.

Screens or grids 22 and 23 may be used if desired, in order to help separate the electrostatic fields. These may be grounded or charged in any

desired way. Other screens may be placed at strategic points for similar purposes. The locations of the various grids and channels can be chosen in order to prevent least counteraction or interference between various fields. The cathodes may be spread over a considerable area in order to help prevent such interference. It is obvious that the cathodes might be separate and the anodes can be joined.

The grids can be charged in any desired combinations or sequence to produce a variety of connections and effects.

In case gas is enclosed in the chambers, a plurality of screens can be used adjacent the grids or other elements or passages in order to minimize spilling over of ions from one channel to another.

Separate anode potential sources joined at the common terminal may be used.

Numerous variations and modifications of the broad concepts disclosed may easily be made without departing from the general principles of the invention.

What I claim is:

1. In an electron discharge device, an envelope, partition means with openings therein and forming a plurality of compartments within said envelope, an anode in each of a plurality of said compartments, a cathode in each of a plurality of said compartments, and means for controlling flow of electrons from any of a plurality of said cathodes to any of a plurality of said anodes.

2. In an electron discharge device, an envelope, a first anode and a second anode within said envelope, a first cathode and a second cathode within said envelope, partition means separating said first cathode and first anode from said second cathode and second anode, other partition means separating said cathodes from said anodes, said other partition means having a plurality of openings to allow passage of electrons from either said cathode to either said anode.

3. The device of claim 2, and means to control flow of said electrons through said openings.

4. In an electron discharge device, an envelope, a first anode and a second anode within said envelope, a first cathode and a second cathode within said envelope, partition means separating said first cathode and first anode from said second cathode and second anode, other partition means separating said cathodes from said anodes, a plurality of openings in said other partition means to allow passage of electrons from either said cathode to either said anode, and a plurality of grids to control flow of electrons through said openings.

5. In an electron discharge device, an envelope, a first anode and a second anode within said envelope, a first cathode and a second cathode within said envelope, partition means separating said first cathode and first anode from said second cathode and second anode and separating said cathodes from said anodes, said partition means having a plurality of openings therethrough to allow passage of electrons from either said cathode to either said anode, and control means adjacent said cathodes for dividing flow of electrons therefrom.

6. The device of claim 5 and including means

to control flow of electrons through said openings.

7. An electron discharge device comprising, an envelope, a first anode and a second anode within said envelope, a first cathode and a second cathode within said envelope, partition means separating said first cathode and first anode from said second cathode and second anode, said partition means also separating said cathodes from said anodes, said partition means having a plurality of openings therethrough to allow passage of electrons from either said cathode to either said anode, and a plurality of grids to control flow of electrons through said openings.

8. An electron discharge device comprising, an envelope, partition means with openings therein and forming a plurality of compartments within said envelope, an anode in each of a plurality of said compartments, a cathode in each of a plurality of said compartments, and control means adjacent said openings for controlling flow of electrons from any of a plurality of said cathodes to any of a plurality of said anodes.

9. An electron discharge device including, a pair of anodes, a pair of cathodes, and grid means for controlling flow of electrons from either said cathode to either said anode.

10. An electron discharge device comprising, an envelope, a first anode and a second anode within said envelope, a first cathode and a second cathode within said envelope, partition means separating said first cathode and said first anode from said second cathode and said second anode, said partition means also separating said cathodes from said anodes, said partition means having a plurality of openings therethrough to allow passage of electrons from either said cathode to either said anode.

11. An electron discharge device comprising, wall means forming four chambers, a cathode in each of two of said chambers, an anode in each of two of said chambers, said wall means having openings therethrough to allow substantially straight line flow of electrons from either of said cathodes to either of said anodes.

12. An electron discharge device comprising, wall means forming four chambers, a cathode in each of two of said chambers, an anode in each of two of said chambers, said wall means having openings therethrough to allow substantially straight line flow of electrons from either of said cathodes to either of said anodes, and control means adjacent at least a plurality of said openings to control flow of electrons therethrough.
